FILLING AND CAPPING MACHINE

Cesare Barbieri, New York, N. Y., assignor to Vortex Cup Company, Chicago, Ill., a corporation of Delaware

Application November 9, 1931. Serial No. 573,737

8 Claims. (Cl. 226—76)

This invention relates to an improved ice cream packaging machine for producing sealed containers of individual servings analogous to the well known ice cream cone but differing therefrom in that the ice cream is sealed in conical paper cups which can be merchandised in individual servings which are protected against contamination and can be carried out for subsequent consumption.

10 It is an object of this invention to provide an improved machine of the class described embracing an intermittently indexed turntable provided with a series of cup holders, the turntable being indexed one cup space at a time to bring 15 a given cup holder successively or progressively beneath a cup dispenser adapted to deliver individual containers from a supply thereof; thereafter carrying the deposited cup beneath an ice cream measuring and delivering mechanism which deposits a predetermined quantity 20 of ice cream in the cup; the cup being next carried beneath a cap delivery mechanism which seats the cap in the cup prior to a final crimping operation which folds and seals the cup 25 rim over a peripheral flange on the cup. Thereafter the cup is lifted out of its pocket to facilitate removal thereof from the table prior to the deposit of another cup in a repetition of the cycle.

30 It is accordingly an object of this invention to provide an improved turntable indexing mechanism together with auxiliary drives which will produce the desired intermittent table drive during idle periods of the various dispenser 35 drives which latter are continuous and correspondingly free from abrupt changes in acceleration which accompany a use of cam drives. By providing a smooth continuous drive for the various dispensers, and operating the table indexing mechanism at the reversal or dead center position of the dispenser movements great 40 improvements in operating efficiency, simplicity, and durability are achieved.

Another object of this invention is to provide 45 an improved machine of the class described wherein the driving mechanisms for the various dispensers or operating units are coordinated with the turntable indexing mechanism in such a way that the individual elements are under 50 the control of the operator so that when starting up the machine at the beginning of a run the various dispensers can be brought into operation sequentially as the first cup deposited in the table pockets progresses beneath the successive operating stations disposed about the turn-

table. This is particularly advantageous in connection with the dispensing mechanisms as it prevents waste of the cups and caps and prevents soiling of the turntable due to the discharge of ice cream before a cup is positioned beneath the delivery spout; and also permits the completion of the cycle on the last cup to be deposited in a table pocket.

It is a further object of this invention to provide an improved machine of the class described wherein a turntable is intermittently indexed by a suitable driving mechanism which also serves to directly actuate a cup dispensing mechanism, cap sealing mechanism, and a lift-out device for facilitating the removal of sealed 65 containers. It is desirable to provide a throw-out clutch or the like for the cup dispensing mechanism, but aside from this refinement the combination of elements mentioned above can conveniently operate as a unit with the turntable drive although functioning when the turntable is stationary and vice versa.

It is also an object of this invention to provide an improved ice cream measuring and dispensing mechanism which will accurately and adjustably 80 measure and deliver a predetermined volume of ice cream into a cup carried therebeneath, the ice cream measuring and dispensing mechanism being driven from a drive common to the machine as a whole while being releasably connected thereto by means which assure the proper timing of the operations upon reconnection of the drive.

It is still another object of this invention to provide an improved machine of the class described 90 wherein a cap dispensing mechanism is driven from a central drive common to all the operating units of the machine, said cap dispensing mechanism being of the top or gravity feed type which is provided with a stock lifting 95 device for rendering the cap feed inoperative without disturbing the operation of the mechanism or its driving connections.

It is an important object of this invention to provide an improved and simplified machine of 100 the class described that will be relatively simple in control and with the minimum of complication in construction and design in order that it may be handled by relatively unskilled labor without requiring excessive or expensive servicing in operation.

Other and further important objects of this invention will be apparent from the disclosures in the specification and the accompanying drawings.

This invention (in a preferred form) is illustrated in the drawings and hereinafter more fully described.

On the drawings:

5 Figure 1 is a side elevation of a machine embodying the features of this invention.

Figure 2 is a plan view thereof.

10 Figure 3 is a rear elevation of the machine with the rear cover removed to show the operating mechanism for the several component devices.

15 Figure 4 is a central vertical section of the complete machine with parts shown in elevation, taken on the line IV—IV of Figure 2.

20 Figure 5 is a horizontal section through the machine base below the level of the table, corresponding to the line V—V in Figure 4.

25 Figure 6 is an enlarged fragmentary vertical section on the line VI—VI of Figure 2 showing the cup dispensing mechanism with parts in elevation.

30 Figure 7 is a section on the line VII—VII of Figure 6 showing the driving mechanism for the cup dispenser.

35 Figures 8, 9, and 10 are plan views of the cap feeding mechanism in successive operating positions during the delivery of a cap.

40 Figure 11 is a central vertical section through the cap feeding mechanism on a line corresponding to XI—XI in Figure 10.

45 Figures 12, 13, and 14 are fragmentary enlarged sections showing the delivery of a cap and corresponding respectively to Figures 8, 9 and 10.

50 Figure 15 is an enlarged cross section on the line XV—XV of Figure 8.

55 Figure 16 is a fragmentary detail partly broken away and sectioned to show the cap forcing plunger seating a cap in a filled cup prior to the crimping operation.

60 Figure 17 is a fragmentary detail partly broken away and sectioned, of the final crimping die which crimps the cup edges down over the flanges of the cap to seal the same.

65 Figure 18 is a fragmentary section on the line XVIII—XVIII of Figure 4 showing the drip cut-off at the bottom of the ice cream delivery spout.

70 Figure 19 is a fragmentary detail elevation of the drip cut-off of Figure 18.

75 As shown the improved rotary or turntable type of ice cream packaging machine embodying the present invention embraces an intermittent turntable driving mechanism for successively or progressively positioning a given table pocket beneath a cup dispenser mechanism adapted to deliver or drop individual containers from a supply thereof into said table pocket, thereafter indexing the table to bring another of a series of container pockets in said table beneath the cup dispenser mechanism, while at another station about the table a cup filling mechanism, including a supply hopper and measuring and delivery means for the ice cream, deposits a measured charge of semi-fluid or plastic ice cream into a cup previously deposited in each table pocket.

80 A further movement of the table serves to bring the filled cup beneath a cap dispensing mechanism where a flanged cap is pushed down into the cup and the cup rim partially turned in over the cap flange. A subsequent indexing of the table brings the cup beneath a cup crimping mechanism which seals the cap in place by completing the crimping of the cup rim over the cap flange. Another indexing movement of the table brings the sealed cup into alignment with a cup discharge plunger which lifts the cup up

out of the table pocket. While these various steps act consecutively relative to a given cup or table pocket, each of the mechanisms about the table act approximately simultaneously at different stations about the table while the latter is accurately indexed and frictionally held between intermittent movements of the table corresponding to the spacing between the cup pockets therein.

85 With the above brief outline of the improved machine in mind it will be convenient to take up the machine elements in substantially the same order. First, however, it will be advisable to describe the particular package selected and for which the illustrated machine was designed 90 to handle. This comprises a conical paper cup 25 similar to individual drinking cups of this type and is best shown in Figure 16 where a portion of the rim 26 has been broken away to show the ice cream 27 and the cap or closure 28, 95 the latter having an upstanding peripheral flange 29 over which the cup rim 26 is turned and crimped to seal the container. It will be understood however that the present invention is not limited to a machine for handling truly 100 conical cups since other types of cups are well known which approximate a frusto-conical form and would not require changes in the machine except perhaps in details such as the internal shape of the cup holders 30 secured to the 105 turntable.

110 The machine proper comprises a base 31 containing the driving mechanism, the base having a bracket 32 on the front thereof for supporting a hollow shaft 33 which carries the hub 110 of a rotary turntable 34. The table 34 is provided with an equally spaced annular series of pockets 35 in which the cup holders 30 are mounted. The table also has a similar series of apertured bushings 36 which cooperate with 115 indexing pins 37 carried by the arm 38 which is provided for the final cup crimping die, to be hereinafter described. The table is driven by a ratchet mechanism which is sufficiently accurate for the dispensing operations while the indexing pins serve to secure more accurate indexing for the crimping die than could be expected from a ratchet mechanism located much nearer to the rotational axis of the table. These indexing pins accurately locate the crimping die 120 relative to the cup holder, this last operation requiring accurate alignment.

125 A sleeve 39 inside the hollow shaft 33 extends down through the bracket 32 to maintain the alignment of the table, and contains guide bushings 40 for a vertically reciprocable rod 41, the upper end of which carries the cap crimping die arm 38 as well as an arm 42 for the cap dispensing mechanism. The table and its shaft 130 revolve on this sleeve, or the sleeve may revolve with the table if desired. In either case the hollow shaft 33 has a ratchet wheel 43 formed thereon with a separate collar 44 adjacent thereto carrying a cooperating pawl 45 and 135 pawl spring 46. The collar 44 is oscillated by means of a rod 47, the rear end of which is connected to a crank pin 48 by a connecting rod 49. Since the pawl and ratchet movement might cause irregular table movements or overrunning 140 thereof the two halves of a split collar 50 are each anchored to a pin 51 at one end and the free ends are joined by a yieldingly arranged clamp bolt 52 which can be adjusted to provide 145 any desired degree of friction between the split 150

collar and a suitable bearing surface on the table shaft 33.

A driving motor 53 is provided with worm reduction gearing 54 on a shaft 55 which carries a gear 56 with which two other gears 57 and 58 mesh. The gear 57 carries the crankpin 48 for driving the table mechanism, while the gear 58 has a similar crankpin 59 connected by links 60 and 61 to vertically reciprocate the rod 41 which carries the cup dispensing and crimping mechanisms. The driving mechanism just described is controlled by the usual switch in the motor electrical circuit, but the cup, ice cream, and cap dispensing mechanisms to be subsequently described are provided with separate mechanical controls in order that they may be successively shut down to complete the cycle on the last cup deposited in a table cup holder, or conversely to start the cycle progressively. The machine is provided with an automatic cup feed mechanism which is driven from an outboard end of the gear shaft 57a, the mechanism and drive being best shown in Figures 3, 6 and 7. The mechanism is mounted on a bracket 62 and comprises a holder 63 for a stack of nested cups, the holder outlet or base having interrupted restrictions 64 which serve to retain the superimposed stack of cups while the bottom cup is being temporarily distorted by passage between the restrictions. The bottom cup is pulled down by oppositely disposed pairs of soft rubber covered fingers 65 carried by oppositely rotating stub shafts driven by gearing 66 from a sprocket wheel 67 which in turn is driven by a chain 68 from a lower sprocket wheel 69 having a bevel gear drive 70 from the gear shaft 57a. The bevel gear on the shaft 57a is under the control of a small hand crank 72 which is utilized to disengage the cup depositing driving mechanism at the will of the operator.

Mounted on top of the base and to one side of the turntable is a supporting bracket 73 for the ice cream dispensing mechanism together with a hopper 74 for supplying ice cream thereto. The particular form of the hopper is not important as long as provision is made to concentrate the flow of ice cream to the hopper outlet 75, in order to prevent the formation of stagnant pockets in the hopper. Adjacent to the hopper outlet 75 a transversely disposed rotary valve chamber 76 is formed in the bracket 73 which chamber contains a valve 77 which is partially cut away at 78 and is intermittently oscillated in such a manner as to alternately bring a measuring pump cylinder 79 into communication with the hopper outlet 75 and with a discharge spout 80 aligned with the position of one of the cup holding table pockets when the table is indexed at any of its stations. The measuring pump cylinder contains a reciprocable piston or plunger 81, the extent of movement of which determines the volume of ice cream delivered to a cup in the table pocket aligned with the spout 80.

The valve 77 is so operated relative to the reciprocating movement of the piston 81 that the valve is in the position of Figure 4 during the in or delivery stroke of the piston, and is rotated approximately 90 degrees clockwise for the out or suction stroke of the piston. Thus while the valve and piston movements must bear a definite relationship, the valve movements are intermittently performed at each end or dead center of the piston movements. In the

illustrated embodiment of the invention both the piston and valve movements are taken from a single crankpin 82 normally driven by a gear 83 which may conveniently mesh with the turntable drive gear 57. The crankpin 82 is journaled in the approximate center of a bar 84 one end of which is provided with an elongated slot or aperture 85 for a pin 86 carried by a lever 87 pivoted at 88 and having its free end 89 coupled to a piston rod 90 having a piston pin bearing 91 in the piston 71. The elongated slot 85 provides a lost motion connection between the bar 84 and the lever 87 and a cam 92, shown dotted in Figure 4, may be rotated by a superimposed hand wheel 93 to vary the extent of the lost motion and thus vary the amplitude of the piston stroke to adjust the volume of ice cream delivered thereby.

The lever pin 86 also acts as a pivot point for the bar 84 which results in an amplification of the range of motion of the free or right-hand end 94 of the bar, which is linked by a pin 98 to a vertically reciprocating member 95 formed on the valve 77. The lower end of the member 95 is provided with a vertically disposed elongated slot 97 in which the pin 98 on the bar 84 operates, the length of the slot 97 determining the dwell period of the valve 77 after this pin 98 in the bar 84 starts on its return movement from either extremity of its motion. In order to prevent the member 95 from following the pin down from its upper position, a friction device shown in Figures 4, 18 and 19 is provided, comprising friction members 99 yieldingly pressed against the sides of the member by adjustable compression spring loading devices 100.

An anti-drip device is shown associated with the delivery spout in Figure 4 and separately in Figures 18 and 19. This comprises a pivoted arm 101 which is bent at an angle for convenience in mounting the pivot 102. This arm carries an outstanding wire like wiper 103 which is intended to be swept across the mouth of the spout as indicated by the dotted line position in Figure 18, to sever pendant threads or drippage of ice cream. The ice cream is preferably in a semi-fluid state which verges on flowability and would otherwise hang from the spout causing subsequent drippage on the table during the indexing movements thereof. By breaking the hanging thread such drippage is prevented without the complication of cut-off valves or drip plates as heretofore used. The anti-drip device is operated by an arm 104 carried by the valve 77, this arm being shown in its horizontal or inactive position in Figure 4. Upon reversal of the valve 77 this arm 104 swings downwardly and during the last part of its movement it strikes the arm 101 shifting the latter to the dotted position shown in Figure 18. The arm 101 is returned to its normal position by a spring 105.

In order to provide a convenient throwoff for stopping the ice cream dispensing mechanism independently of the other mechanisms, the crankpin 82 is mounted on a disc 106 independent of the gear 83 (see Figure 5). The gear 83 is mounted on a sleeve 107 which extends through a journal boss 108 to the outside of the base. A rod 109 extends through the bore of the sleeve and at its inner end carries a key 110 projecting through a slot in the sleeve to engage in a keyway 111 in the disc 106 when the rod is in the position shown in Figure 5. In this position the key 110 transmits the drive 150

from the gear 83 to the disc 106 thus operating the crankpin. The outer end of the rod 109 projects beyond the end of the sleeve 107 and is provided with a knob 112 by which it may be pulled out sufficiently to disengage the key 110 from the keyway 111 thus disengaging the dispenser driving mechanism from the gear 83 which latter rotates as long as the driving motor operates.

10 The outboard end of the sleeve 107 projects beyond the end of its boss and carries a bevel gear 113 keyed thereto which gear serves to drive a cap dispensing mechanism mounted on a bracket 114 located above the boss. A vertical shaft 115 is suitably journaled in the bracket 114 and carries a bevel gear 116 meshing with the gear 113 on the sleeve 107. The upper end of the shaft 115 carries a disc 117 for operating the cap dispenser.

20 The cap dispenser comprises mechanism for removing flanged caps 28 from a stack or magazine and for depositing the cap in position in a filled cup. To this end a magazine or cap stack holder is conveniently formed by four vertical rods 118 mounted in a ring base 119, although it is to be understood that any suitable guiding means for the stacked cups may be utilized. It is preferable to take the caps from the bottom of the stack to avoid complications in feeding and delay when it is necessary to add a new supply of caps. A second ring like member 120 located alongside the magazine forms a guide for a cap seating plunger 121 carried by the arm 42 on the vertically reciprocating rod 41 which extends up through the turntable spindle, as previously described. The rings 119 and 120 form part of a cover member 122 mounted over guideways 123 for the cap selecting and displacing mechanism. In Figures 8 and 9 this cover member 122 has been broken away to more clearly show successive positions of the reciprocating members which comprise a top slide 124 having a connecting rod 125 operated from an eccentric pin 126 on the top of the disc 117, and a lower slide 127 linked to a lever 128 actuated by a roller 129 on the lower side of the disc. The lever 128 is pivoted at 130 to an offset mounting bracket 131 to leave room for a spring 132 which returns the lower slide to its right-hand or retracted position after the roller passes out of contact with the lever 128, as shown in Figures 10 and 11.

50 The upper slide 124 is bifurcated at its outer or left-hand end, the ends 133 so formed being of a length sufficient to slightly underlie the stack of cups when the slide is fully retracted to the position shown in Figure 8. The ends 133 carry plates 134 with undercut points 135 so located as to engage the flange of the lowermost cap in the stack when the slide moves to the left, their preliminary position being shown in Figure 12. These points 135 then force the lowermost cap from beneath the stack and shift it into the recess 136 beneath the guide ring 120 as shown in Figure 13 where the cap is supported by the friction of dependent side blocks 137 of resilient construction such as soft rubber. The lower slide 127 then moves forward to project a central cap detent member 138 up an incline 139 into the position shown in Figure 14. With the cap detent 138 in this position the upper slide is then withdrawn to its starting position, the detent being released, and retracted by its spring 132 after the ends 133 of the upper slide have cleared the guide ring 120.

80 The upper slide is bifurcated both to provide room for the cap detent 138 and for a stack lifting mechanism best shown in Figures 10 and 11. This comprises a finger 140 centrally disposed beneath the level of the bottommost cup in the stack, and mounted on a post 141 which is vertically movable by an eccentric pin 142 operated by a partial rotation of a hand lever 143. When the lever is rotated a half revolution the pin 142 is lifted to its upper position, at the same time elevating the finger 140 to lift the entire stack of caps out of the path of travel of the displacer mechanism, thus rendering the cap dispenser as a whole functionally inoperative, although the mechanism itself continues to operate.

85 The cap seating plunger 121 is vertically reciprocated to force the cap from its position in the recess 136 underneath the ring 120 down into the filled cup 25 as shown in Figure 16. The plunger is provided with outstanding ears 144 which are notched in such a manner as to engage the upstanding rim 26 of the cup to turn it inwardly over the edge of the cap flange 29. This is a preliminary operation performed prior to the actual crimping operation in order to simplify the construction and operation of the crimping die which is located at a subsequent station about the table.

90 The crimping die comprises an outer deflecting ring 145 having a beveled inner edge for deflecting the cup rim inwardly into position for engagement by a crimping die 146 the outer margin of which conforms to the final shape of the inside of the cup rim when crimped over the cap flange. The deflecting ring 145 surrounds the crimping die 146 and its beveled edge seats on a mating beveled surface on the cup holding members 30 in the table pockets, thus steadyng the crimping die which is movable within the deflecting ring. The crimping die is connected to a holder 147, mounted in the arm 38, by a pair of studs 148, and the enveloping deflecting ring is urged against the die by a spring 149 located between the holder and the ring. When the die reaches its limit of downward movement the enveloping ring is lifted relative to the crimping die by contact with the cup holder as shown in Figure 17.

95 After the completion of the crimping operation the next indexing movement of the turntable carries the completed container into position over a lift-out socket 150 which is beveled off on the outer side opposite the turntable axis in order that the filled container will be both lifted and the top thereof tipped outwardly relative to the table to facilitate removal therefrom. The socket 150 is mounted on a rod 151 vertically reciprocable in a suitable guide bracket 152 and the rod is operated by a suitably shaped lever 153 pivoted at 154 and having a cam follower 155 engaging in a cam groove 156 on a cam disc 157 mounted on the shaft 55 from which the various mechanisms previously described take their drive. The operation of the cam disc is thus synchronized with the various mechanisms.

100 A brief description of the operation of the various mechanisms making up the complete machine will now be given.

145 The turntable, about which all the mechanisms are grouped, might conceivably be made with just enough cup pockets to provide one pocket for each of the various mechanisms which operate substantially simultaneously at 150

successive locations about the turntable. Such an arrangement would either involve crowding if the steps between cup locations were held to a reasonable distance, or alternately, if the 5 cup locations were more widely spaced the table indexing mechanism would require too great an angular movement. For these reasons the number of table pockets are preferably in excess of the minimum required number of station locations. While twelve pockets have been shown 10 it should be evident from the foregoing that the exact number is immaterial within reasonable limits.

The turntable is intermittently indexed or rotated one cup space at a time so that the improved pawl and ratchet drive described herein is ideal for the purpose. By providing braking means on the table spindle the table movement is accurately limited to the stroke of pawl and 15 ratchet mechanism by preventing overrun or accidental movements between the indexing movements. Also the drive for the pawl provides a harmonic motion with slow initial acceleration and final deacceleration rates which add to the 20 indexing accuracy.

It will be understood that the table indexing is uniform as to intervals and that between the table indexing movements all the various mechanisms grouped about the table are actuated 25 more or less simultaneously although not operating on the same cup at the same time. The cups progressively pass from one station to the next and the rate of production of filled and sealed containers is dependent on the rate of 30 movement of the table pockets past a given point and not on the ratio of the number of operations relative to the number of table pockets. Thus the final capping and sealing operations can be advantageously split up into stages 35 without affecting the rate of production.

In starting up the machine, assuming that supplies of cups, ice cream and caps have been placed in their respective containers, the motor is started, driving the shaft 55 from which all 40 the mechanisms receive their drive. With this shaft in rotation the turntable drive is energized to index the table one cup space for each revolution of the shaft 55. The capping mechanisms and the lift-out mechanism are also driven from 45 this shaft wherever it is in operation. The cup dispenser and ice cream dispensing valve and pump are also driven from this shaft but the individual drives therefor embody clutch means for rendering the devices inoperative. Thus 50 when starting up the cup and ice cream dispensers are disconnected and the stack of caps lifted out of contact with the cap feed. Then the cup depositor is thrown into operation by means of its clutch and cups are thus deposited in 55 the table pockets as they come to rest beneath the cup depositing mechanism. In the machine disclosed the table will be indexed three spaces before the first cup reaches the ice cream filling station, whereupon the control knob 112 is 60 pushed in to couple the crank disc 106 to the gear 83 to start up the driving mechanism for the measuring piston 81 and valve 77.

The drive to the piston 81 includes an adjustable cam 92 for varying the length of stroke 65 of the piston and thus controlling the volume of ice cream withdrawn from the hopper on the outstroke of the piston and discharged into the cup upon the instroke of the piston. Due to the arrangement of the valve operating mechanism, the valve 77 is reversed substantially at the end 70

points of the piston stroke, the movement from the position shown in Figure 4 serving to actuate the anti-drip device 103 by means of the arm 104 carried by the valve 77.

When further table indexing brings the filled cup beneath the cap seating plunger 21, the stack of caps is lowered into operating position by means of the mechanism operated by the hand lever 143 whereupon the upper slide of the cap depositing mechanism shifts the lowermost cap beneath the cap seating plunger which acts to both seat the cap in the cup and to turn the rim of the cup in over the cup flange. While the plunger ears 144 primarily act at six points about the rim, the intervening portions of the cup rim are also turned over to a greater or less extent so that the final crimping die 146 will contact the original outside surface of the cap rim.

Further indexing movements of the table bring the cup beneath the final crimping die 146 which compresses and irons out the turned over rim of the cup and thus seals the container against leakage or contamination. The next indexing movement of the table brings the completed container over the lift-out plunger which acts to both lift and tilt the cup outwardly to facilitate removal thereof from the table pocket.

I am aware that many changes may be made and numerous details of construction may be varied through a wide range without departing from the principles of this invention, and I, therefore, do not purpose limiting the patent granted hereon otherwise than necessitated by the prior art.

I claim as my invention:

1. In a machine of the class described the combination of a supporting base, a turntable having a series of cup pockets therein and being journaled on said base for intermittent rotation about a vertical axis, various dispensing mechanisms disposed on said base at successive locations about the periphery of said turntable in alignment with the cup pockets therein, said dispensing mechanisms including a cup depositor, measuring and filling means, a cap depositor, and means for sealing caps in the cups after the filling thereof, driving means for said turntable and said various dispensing means, comprising a power unit, a shaft driven therefrom, a plurality of intermeshing gears, one of which is mounted on said shaft and drives the other gears, driving means associated with one of said gears for intermittently indexing said turntable one cup pocket space, friction means associated with said turntable for preventing overrunning or shifting of said turntable between indexing movements thereof, driving means associated with said turntable drive for actuating the cup dispenser, driving means associated with another of said gears for actuating the measuring and filling mechanism, said driving means having clutch means disconnectible from said driving gear for rendering the measuring and filling mechanism inoperative, and means actuated by another of said gears for operating the cap sealing means, said intermeshing gears and their associated driving means being so timed that their associated mechanisms are actuated during the rest period of the intermittently indexed turntable.

2. In a machine of the class described the combination of a supporting base, a turntable having a series of cup pockets therein and being journaled on said base for intermittent rotation 150

about a vertical axis, various dispensing mechanisms disposed on said base at successive locations about the periphery of said turntable in alignment with the cup pocket therein, said dispensing mechanisms including a cup depositor, measuring and filling means, a cap depositor, and means for sealing caps in the cups after the filling thereof, driving means for said turntable and said various dispensing means, comprising 10 a power unit, a shaft driven therefrom, a plurality of intermeshing gears, one of which is mounted on said shaft and drives the other gears, driving means associated with one of said gears for intermittently indexing said turntable one cup pocket space, driving means associated with said turntable drive for actuating the cup dispenser, driving means associated with another of said gears for actuating the measuring and filling mechanism, means actuated by another of said gears for operating the cap sealing means, said intermeshing gears and their associated driving means being so timed that their associated mechanisms are actuated during the rest period of the intermittently indexed turntable, and means operatively connected to said drive shaft for lifting the sealed cups from their table pockets upon completion of the sequence of operations thereon.

3. In a machine of the class described the combination of a supporting base, a turntable, having a series of cup pockets therein and being journaled on said base for intermittent rotation about a vertical axis, various dispensing mechanisms disposed on said base at successive locations about the periphery of said turntable in alignment with the cup pockets therein, said dispensing mechanisms including a cup depositor, measuring and filling means, a cap depositor, and means for sealing caps in the cups after the filling thereof, driving means for said turntable and said various dispensing means, comprising a power unit, a shaft driven therefrom, a plurality of intermeshing gears, one of which is mounted on said shaft and drives the other gears, driving means associated with one of said gears for intermittently indexing said turntable one cup pocket space, friction means associated with said turntable for preventing overrunning or shifting of said turntable between indexing movements thereof, driving means associated with said turntable drive for actuating the cup dispenser, driving means associated with another of said gears for actuating the measuring and filling mechanism, said driving means having clutch means disconnectible from said driving gear for rendering the measuring and filling mechanism inoperative, means actuated by another of said gears for operating the cap sealing means, said intermeshing gears and their associated driving means being so timed that their associated mechanisms are actuated during the rest period of the intermittently indexed turntable, and means operatively connected to said drive shaft for lifting the sealed cups from their table pockets upon completion of the sequence of operations thereon.

4. In a machine of the class described the combination of a supporting base, a turntable having a series of cup pockets therein and being journaled on said base for intermittent rotation about a vertical axis, various dispensing mechanisms disposed on said base at successive locations about the periphery of said turntable in alignment with the cup pocket therein, said dispensing mechanisms including a cup depositor, measuring and filling means, a cap depositor, and means for sealing caps in the cups after the filling thereof, driving means for said turntable and said various dispensing means, comprising

80 a power unit, a shaft driven therefrom, a plurality of intermeshing gears, one of which is mounted on said shaft and drives the other gears, driving means associated with one of said gears for intermittently indexing said turntable one cup pocket space, driving means associated with said turntable drive for actuating the cup dispenser, driving means associated with another of said gears for actuating the measuring and filling mechanism, means actuated by another of said gears for operating the cap sealing means, said intermeshing gears and their associated driving means being so timed that their associated mechanisms are actuated during the rest period of the intermittently indexed turntable, and means operatively connected to said drive shaft for lifting the sealed cups from their table pockets upon completion of the sequence of operations thereon.

85 5. In a machine of the class described the combination of a supporting base, a turntable having a series of cup pockets therein and being journaled on said base for intermittent rotation about a vertical axis, various dispensing mechanisms disposed on said base at successive locations about the periphery of said turntable in alignment with the cup pockets therein, said dispensing mechanism including a cup depositor, measuring and filling means, a cap depositor, and means for sealing caps in the cups 100 after the filling thereof, driving means for said turntable and said various dispensing means, comprising a power unit, a shaft driven therefrom, a plurality of intermeshing gears, one of which is mounted on said shaft and drives the other gears, driving means associated with one of said gears for intermittently indexing said turntable one cup pocket space, friction means associated with said turntable for preventing overrunning or shifting of said turntable between indexing movements thereof, driving means associated with said turntable drive for actuating the cup dispenser, driving means associated with another of said gears for actuating the measuring and filling mechanism, said driving means having clutch means disconnectible from said driving gear for rendering the measuring and filling mechanism inoperative, and means actuated by another of said gears for operating the cap sealing means, said intermeshing gears and their associated driving means being so timed that their associated mechanisms are actuated during the rest period of the intermittently indexed turntable, and means for lifting and tilting said cups in their 115 table pockets upon completion of the sequence of operations thereon.

120 6. In a machine of the class described the combination of a supporting base, a turntable having a series of cup pockets therein and being journaled on said base for intermittent rotation about a vertical axis, various dispensing mechanisms disposed on said base at successive locations about the periphery of said turntable in alignment with the cup pocket therein, said dispensing mechanisms including a cup depositor, measuring and filling means, a cap depositor, and means for sealing caps in the cups 125 after the filling thereof, driving means for said turntable and said various dispensing means, comprising a power unit, a shaft driven therefrom, a plurality of intermeshing gears, one of which is mounted on said shaft and drives the other gears, driving means associated with one of said gears for intermittently indexing said 130 turntable

- turntable one cup pocket space, driving means associated with said turntable drive for actuating the cup dispenser, driving means associated with another of said gears for actuating the 5 measuring and filling mechanism, means actuated by another of said gears for operating the cap sealing means, said intermeshing gears and their associated driving means being so timed that their associated mechanisms are actuated 10 during the rest period of the intermittently indexed turntable, and means for lifting and tilting said cups in their table pockets upon completion of the sequence of operation thereon.
7. In a machine of the class described, a base, 15 a turntable journaled thereon to rotate about a vertical axis, driving means located in said base, means associated therewith for producing an intermittent indexing rotation of said turntable, braking means for said turntable to prevent 20 overrunning thereof, a series of mechanisms disposed on said base about the periphery of said turntable at intervals corresponding to units or multiples of the indexing movement of said turntable, one of said mechanisms comprising 25 a cup dispenser adapted to feed a cup to said turntable after each indexing movement thereof, driving means for said cup dispenser, said cup dispenser being driven from the turntable indexing means, and a throwout for said cup dispenser drive to render the same inoperative without affecting the turntable indexing, said throwout being adapted to automatically reestablish the timing sequence between the cup dispenser and the turntable indexing movements 100 upon reengagement thereof.
